METHOD OF COLD HEADING

Arthur T. Siviter, Detroit, Mich., assignor to
 Budd Wheel Company, Philadelphia, Pa., a
 corporation of Pennsylvania

Application January 22, 1931, Serial No. 510,411

10 Claims. (Cl. 10—27)

My invention has for its object improvements in the art of cold heading and relates more particularly to an adequate control of a blank which is to be cold headed in several successive operations. A more particular object has been to eliminate the difficulty heretofore encountered in successive cold heading processes using a common female die and a hollow punch member incident to the tendency of the blank which was in process of cold heading to recede with the punch and become jambed therein between successive heading operations performed by successive punches. I have obviated this difficulty by forming one or more of my female dies of a configuration adapted to insure the jamming of the nut within the female die assembly during the recession of the punch.

Other objects and advantages of my invention will be obvious from a reading of the subjoined specification in the light of the attached drawing, in which:

Fig. 1 is a central sectional view of my die assembly illustrating the first step in my improved process.

Fig. 2 is a similar view through the female die and the first punch coacting therewith illustrating the second step in the process.

Fig. 3 illustrates a further step.

Figs. 4 and 5 illustrate my two female dies, and Fig. 6 illustrates the stud constituting the finished product of my method.

Referring to the drawing by reference characters, the numeral 10 indicates a blank which is to be cold headed, the cold heading operation in the present case constituting the formation of a trunk stud having an enlarged annular flange 24 in its central region and a second enlarged portion 23 adjacent thereto. The cold heading operation by which the stud is formed from the blank 10 is performed in two successive steps in the first of which the enlarged portion 23 is formed by upsetting the blank within the female dies. The second step consists in the formation of the annular collar 24 by the coaction of one of these female dies with a second die in the nature of a punch.

These operations were performed in accordance with the prior art by the coaction of a single set of female dies with a pair of punches which were mounted for reciprocatory motion in two dimensions at right angles to each other in order that these punches might successively coact with the single female die assembly. The punches were provided with hollow portions adjacent their outer ends adapted to receive the end of the

blank 10 and considerable difficulty was encountered incident to the tendency of the blank to be slightly upset within the hollow end of the punch and to jamb within the punch and to be withdrawn therewith.

My improved cold heading die assembly is similar to those of the prior art except for certain important details as to the formation of one or more of the dies whereby this jamming effect is obviated. This die assembly consists of the die holder 11 in which are mounted front and rear female dies 12 and 13 held in place between a suitable anvil 14 on the rear side and a shoulder 16 formed adjacent the outer end of the die holder to coact with a complementary shoulder 16' on the outer die 12. An ejector 15 is adapted to reciprocate within an opening in the anvil 14 and eject the finished blank at the end of the cold heading operation. This ejector performs the additional function of acting as a limiting stop for the movement of the blank into the female die assembly. The punch assembly consists of a head 18 within which a pair of punches 19 and 20 are mounted, the head 18 being provided with means (not shown) for effecting a reciprocation thereof toward and from the solid female die assembly and at right angles thereto, these motions effecting the heading operations and the alignment of successive punches with the female die assembly, respectively. By "solid" female die, is meant a die which is not divided longitudinally of the die recess for lateral separation at the time of extrusion, although it may be formed of laterally-divided parts to be held together while the blank is extruded longitudinally therefrom, or composed of a plurality of die sections, as shown in the drawing, or the equivalents thereof.

Each of the punches 19 and 20 is provided with a hollow bore adapted to receive the end of the stud in process of formation. The reciprocation of the punch 19 upsets a portion of the blank within the dies 12 and 13 and thus forms the enlargement 23 upon the body of the stud. In the second cold heading step, in which the punch 20 coacts with the female dies, the collar 24 is formed by the upsetting of the metal adjacent the center of the stud within recessed portions 21 and 22 formed within the meeting ends of the punch 20 and die 12 respectively. Upon the completion of the cold heading operation suitable threads are formed upon the stud to form the finished article of Fig. 6.

In order to prevent the retreat of the stud with the punch 18, the stud is provided with

- an enlarged portion adapted to jamb within one of the female dies, this portion tapering away from the outer end of the dies. In order to effect this formation one or both of the dies is provided with a bore 25 tapering slightly away from the mouths of the dies. As a result of this formation a part of the metal of the stud is upset within the bore and jambmed within the female die or dies and prevented from being withdrawn with the punch 19. As a consequence of this fact the blank is retained firmly within the female die assembly until after the second die 20 has formed the annular collar 24 thereon and retreated from the female dies. After this operation the ejector 15 is actuated to force the finished blank out of the female die assembly. In forcing the stud from this assembly the conical configuration thereof is destroyed incident to its passage through the most restricted portion of the dies. My invention thus consists in the formation of a temporary truncated cone upon the body of the stud to insure its retention within the female die during the entire cold heading operation. Even though the end of the blank which is received within the punch 19 be upset sufficiently to cause a tendency to jamb within the punch, the jambing within the dies 12 and 13 incident to the formation of the truncated cone will exert a grip upon the blank overcomes this tendency to recede with the punch.
- While I have illustrated but a single embodiment of my invention, I wish it to be understood that others will be obvious to those skilled in the art and I do not accordingly intend to be limited except by the scope of my subjoined claims as interpreted in the light of the prior art and the generic spirit of my invention.
- I claim:
1. The method of cold heading a metal blank in successive steps which comprises upsetting plural portions of said blank within a female die in such a manner that said upset portions flare away from the mouth of the respective parts of said die and become jambmed therein, and performing successive cold heading operations by the coaction of successive punches with said female die and extruding said upset blank outwardly of said die through the mouth thereof.
  2. The method of cold heading a metal blank in successive steps through the coaction of a plurality of dies on the one hand with a single die on the other which comprises effecting a jambing of the blank within plural portions of the single die flaring outwardly away from the point of entry thereof and performing the successive cold heading operations by the coaction of the first-named dies successively with said single die and forcing said formed blank outwardly through the point of entry of said die, the said single die with the flaring portions being a solid die.
  3. A die assembly adapted for successive coaction with a plurality of opposed dies, said assembly including a solid female die having plural portions of its bore flaring away from the point of entry and ejection of the blank with respect thereto.
  4. The method of cold heading a metal blank in successive steps through the coaction of a plurality of dies on the one hand with a single die on the other which comprises forming a plurality of flared portions on said blank within the single die and performing the successive cold heading operations by the coaction of the first-named dies successively with said single dies and ejecting said formed blank out of said die through the point of entry of said blank into said die to reform the portions of the blank formed by said flared die portions.
  5. The method of cold heading a metal blank in successive steps which comprises upsetting and jambing portions of the blank within successive parts of a solid female die and performing successive cold heading operations by the coaction of successive punches with said female die and ejecting said formed blank out of said die through the point of entry of said blank into said die.
  6. The method of cold heading a metal blank in successive steps which comprises upsetting and jambing portions of the blank within successive parts of a female die in such a manner that the upset portions flare away from the mouth of the die and performing successive cold heading operations by the coaction of successive punches with said female die and ejecting said formed blank out of said die through the point of entry of said blank into said die to destroy the flares of said portions.
  7. A die assembly for successive coaction with a plurality of opposed dies, said assembly including a female die consisting of separate die blocks each having a portion of its bore flaring away from the point of entry and ejection of the blank with respect thereto.
  8. The method of cold heading a metal blank through the coaction of a plurality of dies on one hand with a single die on the other which comprises jambing different portions of the blank in successive parts of said single die, and thereafter extruding said blank through the mouth of said single die to accurately size the blank.
  9. The method of cold heading a metal blank through the coaction of a plurality of dies on one hand with a single die on the other which comprises jambing different portions of the blank in successive parts of said single die, and thereafter extruding said blank through restricted portions of said single die to accurately size the blank.
  10. The method of cold heading a stud which comprises forcing a metal blank into a female die having plural contours while upsetting said blank in the same, whereby to form tapering enlarged portions thereupon flaring away from the point of entry of said blank in said die sections, and whereby said blank is jammed in said die sections, further upsetting said blank to form a shoulder substantially centrally thereupon, and withdrawing the cooperating die element and ejecting said blank through the reduced size openings of said contoured female die.

ARTHUR T. SIVITER.
